UNITED STATES PATENT OFFICE

FRANK BERN, OF CLEVELAND, OHIO

DESIGN FOR A MASK MEMBER FOR PHOTOGRAPHIC PRINTING DEVICES

Application filed October 28, 1931. Serial No. 41,548. Term of patent 7 years.

To all whom it may concern:

Be it known that I, FRANK BERN, a citizen of the United States, residing at Cleveland, in the county of Cuyahoga and State of Ohio, have invented a new, original, and ornamental Design for a Mask Member for Photographic Printing Devices, of which the following is a specification, reference being had to the accompanying drawings, forming part thereof.

In said drawings, Fig. 1 is a plan view of a mask member for a photographic printing device, said mask member showing my new design; and Fig. 2 is a cross sectional view of said mask member on the line 2—2, Fig. 1.

I claim:

The ornamental design for a mask member for photographic printing devices, as shown.

FRANK BERN.
